UNITED STATES PATENT OFFICE.

SIEGMUND JACOBSON, OF NEW YORK, N. Y.

DESIGN FOR AN APRON.

SPECIFICATION forming part of Design No. 20,697, dated April 28, 1891.

Application filed March 24, 1891. Serial No. 386,268. Term of patent 3½ years.

To all whom it may concern:

Be it known that I, SIEGMUND JACOBSON, of New York, in the county and State of New York, have invented and produced a new and 5 original Design for Aprons, of which the following is a full, clear, and exact specification.

Reference is to be had to the accompanying drawing, forming a part of this specification, which is a perspective view of an apron embodying my design.

The leading feature of my design consists of an apron having a V-shaped bib or front arranged in connection with a broad semicircularly-shaped collar.

15 The bib or front 10 is in outline of elongated-V shape, the point of the V extending some distance below the waist-line of the apron and lying in the median line of the apron. The edges of the bib or front are embellished by a narrow border 11, of plaid pattern, disposed to present the appearance of diagonal intersecting lines and intervening irregularly-recurring open spaces. Upon the front of the bib or front are disposed elongated triangular revers 12, of plaid pattern, 20 presenting the appearance of alternating single and grouped vertical and horizontal intersecting lines and regularly-recurring open

spaces aligning horizontally and vertically, the revers defining a V-shaped opening in the upper end of the bib or front. Upon the upper ends of the revers is imposed a collar 13, of broad semicircular outline and embellished at its edges by a narrow border 14, of like appearance to that of the bib or front.

35 The apron 15 is of conventional outline, embellished at its edges by a narrow border 16, of like appearance to that of the bib or front, and on the ends of its strings 17 are imposed substantially square tabs 18, of like facial appearance to the borders of the bib or front, apron, and collar. Slightly above the transverse center of the bib and at one side of its median line appears a pocket 19, the mouth of which ranges diagonally, and the 40 front of the pocket is embellished by a triangular facing 20, of plaid pattern, disposed in like manner to the facial pattern of the revers 12.

I claim—

45 The design for aprons herein described, and shown in the accompanying drawing.

SIEGMUND JACOBSON.
